JAR WASHER

Carl Raymond Carlson and Robert S. Bonzi, Rockford, Ill., assignors, by mesne assignments, to W. F. and John Barnes Company, Rockford, Ill., a corporation of Illinois

Application August 22, 1952, Serial No. 305,738

8 Claims. (Cl. 134—70)

The present invention relates to an improved article washing or treating apparatus, and more particularly to an apparatus for washing a series of bottles, jars, or like articles as they pass along a predetermined path.

In order economically to wash or otherwise treat jars, it is necessary that the articles be conveyed through the treating apparatus as rapidly and as closely together as possible so that a large number of articles may be treated in a given amount of time. However, when conveying bottles or jars or similar easily breakable articles, the relatively high speeds necessary create considerable vibration and shock which often tend to break the articles. Furthermore, the prior art devices often inadequately clean jars. It is, therefore, an object of this invention to provide a jar or bottle washer which conveys the articles at relatively high speeds without danger of breakage and which effectively cleans the articles.

A more specific object of this invention is to provide an apparatus of the above described type with a novel article conveying mechanism by which a series of closely adjacent jars or other like articles may be conveyed rapidly through the apparatus without breakage while at the same time rotating the jars so that their surfaces are uniformly presented to the washing or treating mechanism of the apparatus, whereby the jars may be effectively cleaned.

Another object of the present invention is to provide a conveying mechanism of the above described type which may be easily adjusted to accommodate various sizes of jars or other like articles.

Another object of this invention is to provide a jar or bottle washing apparatus of the above described type which includes a series of spray nozzles disposed adjacent the conveying mechanism, which nozzles may be adjusted to direct the spray at various angles for effectively cleaning jars of various sizes and shapes.

Other objects and advantages of the present invention will be apparent from the following description and the accompanying drawings, wherein:

Fig. 1 is a perspective view, showing a jar washing apparatus which embodies principles of this invention;

Fig. 2 is a front elevational view of the apparatus shown in Fig. 1;

Fig. 3 is a vertical cross sectional view taken along line 3—3 in Fig. 4;

Fig. 4 is a horizontal cross sectional view taken along line 4—4 in Fig. 3;

Fig. 5 is a fragmentary vertical cross sectional view taken along line 5—5 in Fig. 3;

Fig. 6 is a cross sectional view, showing a spray nozzle which may be utilized with the apparatus of this invention;

Fig. 7 is a fragmentary horizontal cross sectional view similar to Fig. 4, but showing a modified form of this invention; and

Fig. 8 is a partial cross sectional view taken along line 8—8 in Fig. 7.

2

Referring now more specifically to the drawings, wherein like parts are designated by the same numerals throughout the various figures, a jar or bottle washer, involving the principles of this invention, is shown in Figs. 1 and 2 and is generally designated by the numeral 10. The washer 10 includes an elongated cabinet 12 having sides 14 and 16, ends 18 and 20, a bottom 22, and a top 24 (see Figs. 3 and 4). The sides, ends, bottom, and top are preferably constructed from sheet metal and joined along their adjacent edges by welding or any other suitable means. The cabinet may be suitably reinforced by angle irons disposed along its edges and corners. For example, angle irons 26, 28, 30, and 32 may be secured along the vertically extending corners of the cabinet. Preferably, these last mentioned angle irons extend downwardly beneath the cabinet 12 to provide support legs, as shown best in Fig. 1. The legs may be reinforced and braced by any suitable structure, such as the bracing structure shown in Fig. 1 and generally designated by the numeral 34. The side 16 of the cabinet is provided with an elongated door panel 36 (see Figs. 1 and 5), preferably transparent, which panel is hinged to the side, as at 34. One or more chains 38 are connected between the upper or outer edge of the door panel 36 and the upper edge portion of the cabinet to support the door in an open position, as shown in Fig. 1. A latch mechanism 40, which may be of any suitable design, is provided for retaining the door in a closed position.

Extending the length of the cabinet are a pair of generally horizontally disposed guide or support rails 42 and 44 (see Figs. 3, 4, and 5). These rails are supported on and secured to a series of spaced inverted U-shaped brackets 46, which are in turn supported on horizontally disposed braces 48. The braces 48 are supported by having one end welded or otherwise secured to a longitudinally extending angle iron 50, which is disposed along the front side 16 of the cabinet, as shown in Fig. 5. The opposite end of the braces or angle irons 48 may be secured as by welding to a longitudinally extending angle iron 52, or to vertically extending angle irons 54, as shown in Figs. 4 and 5. It should be noted that the guide or support rails 42 and 44 are spaced apart sufficiently so that a jar or bottle 56 may rest thereon in an inverted position, as shown in Fig. 5, with the mouth of the jar sufficiently open to receive the cleaning fluid, as herein-after more fully described.

Adjacent one side of and above the rails 42 and 44, there is positioned a second pair of longitudinally extending guide rails 58 and 60. As shown best in Fig. 5, the guide rails 58 and 60 are supported in spaced relationship by a bracket 62, which bracket terminates at its lower end in a generally horizontally extending flange 64. As shown in Figs. 4 and 5, a series of these brackets 62 is provided at spaced intervals along the cabinet, and the brackets are supported on the previously described cross braces 48. The brackets 62 are preferably secured to the braces 48 by means of a bolt 66 extending through the horizontally disposed flange 64. The bracket 62 is provided with an elongated slot 68 through which the bolt 66 extends. By this structure, upon loosening the bolts, the brackets 62 may be moved back and forth transversely of the cabinet to position the vertically spaced guide rails 58 and 60 at various locations with respect to the horizontally spaced guide rails 42 and 44 in order to accommodate different sizes and shapes of jars or bottles. A washer 70 having a diameter greater than the width of the slot 68 is disposed on the bolt between its head and the flange 64 to facilitate the sliding movement between the flange and the bolt and to enable the bolt to be tightened without interference from the slot.

Above the guide rails 42 and 44, there is still an-

considerable por

tion of the outer end of the pipe 166 no nozzles are provided. With this structure, the jars, after being rinsed by clear water, are advanced through a portion of the cabinet in which there are no sprays so that the water may drain from the jars.

The bottom 22 of the cabinet is inclined, as is shown in Fig. 3, so that the water drained from the jars flows down the bottom to discharge pipes. It should be noted that if desired the lower portion of the cabinet may be divided into two chambers by a baffle plate 182 which is disposed between the ends of the detergent supply pipe 164 and the clear water supply pipe 166. Thus, the draining rinse water may be separated from the draining fluid detergent. A drain spout 184 is provided for conducting the draining rinse water to a drainage chute 186, as shown in Figs. 1, 2, and 3. A similar drainage spout 188 is connected to the bottom of the cabinet for conveying the draining fluid detergent to a drainage chute 190.

In order to prevent vapor and fumes from escaping into the atmosphere surrounding the cabinet, an exhaust duct 192 is connected to the interior of the cabinet through the top 24, as shown in Figs. 1 and 2. The exhaust duct may be extended to convey the fumes and vapor to any desired point. Preferably, an exhaust fan, not shown, is disposed within the duct to suck the fumes and vapor out of the cabinet.

Referring specifically now to Figs. 7 and 8, there is shown a modified structure resiliently biasing the inner runs of the V-belts against the jars and toward the opposite guide rails. This structure includes a pair of resilient spring fingers 194 and 196 which are integrally connected by a flat plate member 198. Preferably, the spring fingers and plate member are constructed from a single sheet of spring metal. The spring fingers are secured to a mounting block 200 by screws 202. As shown in Fig. 8, the mounting block 200 is connected to the longitudinally extending plate 72 by one or more screws 204, and the block extends from the plate between the vertically spaced V-belts. The outer free ends of the spring fingers terminate in curved belt engaging portions 206. The curved end portion of the finger 196 is provided with flanges 208 and 210 which are flared outwardly so that they enclose the opposite sides of the V-belts. The curved end portion of the finger 194 is provided with similar flanges 212 and 214. These flanges eliminate any sagging in the V-belts and also maintain the belts in alignment with the spring fingers so that there is no danger that the fingers will become disengaged from the belts. While only one spring finger assembly has been shown in Fig. 8, it is obvious that several such assemblies should be positioned along the length of the V-belts in accordance with the requirements dictated by the particular size and length of the belts.

The operation of the bottle or jar washer of this invention is as follows. A series of jars 56 is fed to the cabinet of the washer by any suitable means, and as the jars approach the cabinet, they are turned to an inverted position by the twister bar assembly 216, shown in Figs. 1 and 2. The jars enter the cabinet through an opening 218 in the end 18. As the jars enter the cabinet, they are supported on the horizontally spaced support rails 42 and 44, and they are forced between the vertically spaced guide rails 58 and 60 and the V-belts. The electric motor 142 is then energized to drive the belts, and the speed of the belts may be adjusted by the varying-speed drive 144. As the inner run of the V-belts advances along the path of travel of the jars, it frictionally engages the jars and causes them to advance therewith. It should be noted that the V-belts press the jars against the opposite guide rails 58 and 60 so that as the jars advance, they are also frictionally engaged by the guide rails. Since the belts move along the path of travel relative to the opposed guide rails, the jars are in effect rolled along the rails. This rotation of the jars as they are advanced through the

cabinet causes all of their surfaces to be uniformly presented to the washing and rinsing sprays so that they are thoroughly clean. Before the motor has been energized to drive the belts, the valves 172 and 180 should be opened to permit the fluid detergent to flow into the pipe 164 and out through the spray nozzles connected thereto and clean rinse water to flow through the pipe 166 and out through the nozzles communicating therewith. It is, of course, assumed that the spray nozzles have previously been adjusted for the size and type of jar which is being passed through the apparatus. After the jars pass over the detergent spraying nozzles and the rinse water spraying nozzles, they pass along a portion of their path of travel during which the water is allowed to drain. The jars are discharged from the cabinet through the opening 220 and onto any suitable type of discharge conveyor 222.

From the above description, it is seen that the present invention provides a simple and efficient apparatus, wherein the jars are not only conveyed, but are also rotated so as to present all of their surfaces to the cleaning sprays for effective cleaning. Furthermore, since the jars are always held between the belts and the opposed guide rails with a substantially uniform pressure, vibrations and shocks between the jars and the apparatus and each other are greatly reduced to eliminate breakage of the jars. In addition, it should be noted that the simple frictional feeding belts enable the jars to be positioned in abutting relationship so that there can be little if any relative movement between the jars along the path, whereby shocks between the jars are further reduced to reduce breakage. It is, therefore, seen that the novel jar feeding mechanism of this invention in combination with the novel structure and location of the fluid nozzles provides a simple and economical apparatus which is capable of fully carrying out the objects set forth hereinabove.

While the preferred embodiments of the present invention have been described and illustrated herein, it is obvious that many structure details may be changed without departing from the spirit and scope of the appended claims.

We claim:

1. An apparatus for treating breakable glass jars and the like, comprising a pair of horizontally disposed elongated parallel spaced fixed support means adapted to support thereon a series of inverted jars with at least a portion of the open mouths of the jars uncovered, elongated guide means disposed for frictional engagement with side surfaces of the jars supported on said support means, an endless belt having a portion thereof disposed parallel to said guide means for frictional engagement with opposite side surfaces of the jars, means for resiliently biasing said portion of the endless belt toward the guide means and against the jars with substantially uniform pressure, a series of spray nozzles disposed for projecting jar treating sprays upwardly between said spaced support means and into the jars, an elongated guide member disposed above said support means for engaging upper closed ends of the jars and preventing the jars from lifting unduly under the influence of the sprays, and means for driving said endless belt to move said portion relative to said guide means for advancing and rotating jars therebetween whereby all of the interior surfaces of the jars are presented uniformly to the sprays projected by said nozzles.
2. An apparatus for treating breakable glass jars and the like, comprising an elongated generally horizontally arranged housing having jar inlet and outlet openings at opposite ends, a pair of horizontally disposed elongated spaced support members mounted within said housing for supporting a series of inverted jars with at least a portion of the open mouths of the jars uncovered, an elongated guide means disposed within said housing for frictional engagement with sides of jars on said support means, an endless belt mounted within said housing with a portion thereof disposed parallel to said guide means.
